(57) **CLAIM**

The ornamental design for a motor guard as shown and described.

DESCRIPTION

FIG. 1 is a front perspective view of a motor guard showing our new design;

FIG. 2 is a rear exploded perspective view thereof; and,

FIG. 3 is a front exploded perspective view thereof.

The dash-dash-dash broken lines are included for the purpose of illustrating portions of the motor guard that form no part of the claimed design. The broken lines in FIG. 3 depict a motor which forms no part of the claimed design.

1 Claim, 3 Drawing SheetsFIG. 1

FIG. 2

FIG. 3
